UNITED STATES PATENT OFFICE.

FRANK W. DINE, OF MINSTER, OHIO, ASSIGNOR, BY MESNE ASSIGNMENTS, TO THE NATIONAL AUTOMATIC TOOL COMPANY, OF RICHMOND, INDIANA, A CORPORATION OF INDIANA.

DRILLING MACHINE.

Application filed August 1, 1923. Serial No. 655,128.

To all whom it may concern:

Be it known that I, FRANK W. DINE, a citizen of the United States, residing at Minster, in the county of Auglaize and State of Ohio, have invented certain new and useful Improvements in Drilling Machines, of which the following is a specification.

It is one of the principal objects of my invention to provide a drilling machine in which there may be easily installed one of three distinct drives, to wit, a tight and loose pulley drive, a single clutch drive and a double clutch drive. The latter is more commonly known as the tapping attachment or reversing mechanism, since it provides for a reverse motion of the spindle.

The principal advantage of the three drive construction is, that one can take out one shaft, such as the single clutch drive, and insert another one in its place without the necessity of unbolting and removing the numerous housing parts that must be taken off in other drilling machines to remove a shaft.

It is also another object of my invention to mount the shafts and the spindle in vertical alinement to facilitate machining operations and to properly lubricate them. To supply oil to these shafts there is provided at the lower end of the first one, a gear pump that is submerged at all times in oil in the lower part of the main housing, which acts as an oil reservoir.

Other important and incidental objects will be brought out in the following specification, and particularly set forth in the subjoined claims.

In the accompanying drawings illustrating my invention, Figure 1 is a perspective view of my improved drilling machine. Figure 2 is a longitudinal sectional view taken through the head of the machine, showing the double clutch drive and the gear oil pump. Figure 3 is a cross sectional view taken on the line 3-3 of Figure 2, showing the reverse gears. Figure 4 is a longitudinal sectional view taken on the line 4-4 of Figure 2, showing the tight and loose pulley drive in the machine. Figure 5 is a longitudinal sectional view taken on the same line of Figure 2, showing the drilling machine equipped with the single clutch drive. Figure 6 is a detail side view of the gear oil

pump. And Figure 7 is a bottom plan view of the latter.

Throughout the specification and drawings, similar reference characters denote corresponding parts.

Referring to the accompanying drawings for a detailed description of the form of embodiment of my invention illustrated therein, the numeral 1 designates a drilling machine housing having a front bearing portion 2 for a spindle 3. One of the drives which I have provided for the latter is a tight and loose pulley drive which will now be described.

In Figure 4, which illustrates this form of drive, the numeral 4 designates a horizontal pulley shaft that is journaled in ball bearing members 5, 5 pressed in a removable shaft housing 6 for which there is a removable cover 7 and to which end plates 8, 8 are bolted.

Mounted on the right hand end of the pulley shaft 4 in Figure 4, is a tight pulley 9 and a loose pulley 10 to receive a power-driven belt (not shown). Within the housing there is mounted on the pulley shaft 4 a miter gear 11. The latter meshes with a miter gear 12 on a vertical shaft 13 below a top retaining nut 14. At its upper end the shaft 13 is journaled in a ball bearing member 15 fitted in a groove in the inner surface of the shaft housing 6, and at its lower end said shaft 13 is journaled in a bearing member 16 mounted in the lower part of the housing 1. Keyed to the shaft 13 just below the bearing member 15 is a gear 17 which drives the spindle 3 through an intermediate train of gearing hereinafter to be described.

In Figure 5 I have shown a single clutch drive shaft 18 which has been substituted for the vertical shaft 13 shown in Figure 4. This substitution may be easily effected in the following manner. A nut 19 and a pump pulley 20 on the left-hand end of the pulley shaft 4 are removed, whereupon the end plates 8, 8 are taken off to permit the shaft 4 to be pulled out. The nut 14 is then removed from the vertical shaft 13 to permit the miter gear 12 to be taken off, after which the shaft housing 6 is lifted out. The vertical shaft 13 is then free to be pulled out

after a nut 21 on its lower end is removed through a hole in the bottom of the housing 1 that is opened by unscrewing a closure nut 22.

After the shaft 13 is removed, the shaft 18 is substituted for it in the housing 1, after which the shaft housing 6 is replaced in the latter. The miter gear 12 is then applied to the shaft 18 and the nut 14 screwed on its upper end and the nut 21 on its lower end, after which the closure nut 22 is screwed in place. A pulley shaft 4 which is shorter than the first one, since the loose pulley is omitted from it, is then adjusted above the vertical shaft 13 to bring the miter gear 11 into mesh with the miter gear 12, after which the end plates 8, 8 are bolted to the shaft housing 6. The pump pulley 20 and nut 19 are then applied to the pulley shaft.

Instead of the gear 17 being keyed to the vertical shaft as in Figure 4, it is keyed to a driven clutch member 23 which has in its lower end a conical bore 24 into which there is adapted to be pressed a conical driving member 25 that is keyed to the shaft 18 for a sliding movement thereon. (See Figure 5.)

The driving member 25 is shifted along the shaft 18 by a shoe 26 which freely fits into a grooved sleeve 27 secured to said driving member. The shoe 26 is pinned to a vertical sliding bar 28 which may be reciprocated by any suitable means.

When the driving member 25 is pressed into engagement with the driven member 23, the shaft 18, when rotated by the pulley shaft 4, will rotate the gear 17 by which the spindle 3 will be turned through the train of gearing to be hereinafter described.

I have also provided for my drilling machine a double clutch drive shaft 29 shown in Figure 2. This shaft 29 may be substituted for the shaft 18 in the housing 1 in the same facile manner that the latter shaft was substituted for the shaft 13 in said housing.

The shaft 29 carries not only the driving clutch member 25 and the driven clutch member 23 to which the gear 17 is keyed, but also reversing clutch means now to be described. Referring to Figure 2, the numeral 30 designates a conical driven member mounted on the lower end of the shaft 29, and into engagement with which the driving member 25 is adapted to be pressed. Keyed to the driven member 30 is a gear 31 which meshes with an intermediate gear 32 that in turn is in mesh with a gear 33 fast on a jack shaft 34 journaled in parallelism with the shaft 29 in an upper bearing 35 and a lower bearing 36 in the housing 1.

Keyed to the upper end of the jack shaft 34 is a gear 37 which meshes with the driving gear 17. When the driving member 25

is in engagement with the driven member 23, the gear 17, which is keyed to the latter, will rotate the jack shaft 34 in a positive direction. Then, when said driving member 25 is shifted into engagement with the conical member 30 on the lower end of the shaft 29, it will rotate the jack shaft 34 in a reverse direction for the reason that an intermediate gear 32 is meshed with the gears 31 and 33. (See Figures 2 and 3.)

There is also mounted on the jack shaft 34 a sliding gear 38 which engages a change speed gear 39 keyed to a back gear shaft 40 journaled in the spindle bearing portion 2 of the housing 1, to give the machine two mechanical speed changes. (See Figure 2.)

The spindle bearing portion 2 of the housing 1, which is in the upper front part of the machine, terminates at its lower end in a skirt or flange portion 41 through which the back gear shaft 40 and the spindle 3 project. Removably bolted to this flange portion of the spindle bearing part 2 is a flanged or cup-shaped oil-holding member or cover 42. (See Figures 1 and 2.)

Secured to the lower end of the back gear shaft 40 is a gear 43 which meshes with a horizontal gear 44. The latter is secured to a spindle-driving sleeve 45 that is rotatable in a bushing 46 secured in the bearing portion 2 of the housing 1. Pinned in the sleeve 45 are keys 47 which enter longitudinal grooves in the periphery of the spindle 3 for the purpose of driving the latter.

The gears 43 and 44 are mounted on the shaft 40 and sleeve 45 respectively to rotate within the flanged cover 42, which not only contains oil for the lubrication of these gears, but it may be readily taken off to permit the replacement of them. Furthermore, the location of these change-speed gears at the bottom of the spindle bearing portion 2 of the housing 1, provides a driving connection between the back gear shaft 40 and the spindle 3 that is in close proximity to the work, thus eliminating the torque or twist to which the spindle is incident when driven from its upper end.

For the purpose of supplying an abundance of oil to the various working parts within the housing 1, the following means are provided. In the first place, the shaft 29 is preferably constructed of a piece of hollow tubing to permit oil to be discharged from its upper end upon the miter gear 11 which throws it upon the working parts. The opening in the housing 1 below the shaft 29, instead of being closed by the nut 22, has screwed into it a nut 48 having an enlarged lower end which contains two cavities in which there freely turn two oil pump gears 49 and 50. (See Figures 2, 6 and 7.) These gears are covered by a bottom plate 51 which is secured by cap screws 52 to the nut 48.

The gear 50 has an upwardly projecting driving shaft portion 53 through which and through the gear, an axial hole extends for communication at its top end with the hole 5 that runs through the shaft 29. The latter is connected with the driving shaft portion 53 of the gear 50 by a Woodruff key 54, so that said gear may be driven by said shaft 29. (See Figure 2.)

10 A hole 55 is drilled through the nut 48 into the gear cavities to supply oil to the latter from a reservoir 56 which the housing 1 forms and with which said hole 55 communicates. (See Figures 6 and 7.)

15 In the bottom plate 51 a pump discharge hole 57 is drilled, but not all the way through it; and directly under the gear 50 a hole 58 is drilled in said bottom plate, but not all the way through it, to communicate 20 with the hole in said gear. These two holes 57 and 58 are connected by a lateral hole 59 which contains in its outer end a plug 60. (See Figure 7.) This lateral hole 59 permits the oil to run from the hole 57 in the 25 discharge side of the bottom plate to the hole 58 in the latter which communicates with the hole in the gear 50, that in turn communicates with the hole in the shaft 29.

It will now be seen that when the gears 49 30 and 50 are rotated by the shaft 29 which is connected to the latter gear, they will force the oil through the holes 57, 59 and 58 into the hole in said shaft for discharge from its upper end upon the miter gear 11 that 35 throws it upon the working parts. The shafts 29, 34 and 40 are all mounted vertically and in parallelism with the spindle 3 to permit the oil to run down over them upon the operating mechanism and to facilitate 40 machining operations.

It will also be observed from the foregoing description that it is readily possible in my drilling machine to obtain one of three 45 distinct drives, to wit, a tight and loose pulley drive, a single clutch drive or a double clutch one, by substituting any one of the shaft 13, 18 or 29 for the other in the drive-shaft receiving portion of the housing 1. These shafts are all of equal length; they are 50 confined at the same points in the housing and are not a bolted attachment. Therefore, one may be substituted for the other with ease and without the necessity of bolting on a separate housing for each of them 55 as in other types of machines.

Having described my invention, I claim:

1. In a drilling machine, the combination 60 with a housing having a drive shaft receiving portion and a front bearing portion, of a spindle movable in the latter, a series of different spindle-driving shafts, bearing means in the drive shaft receiving portion of the housing to receive any one of said shafts without change, a removable top part 65 for the drive shaft receiving portion of the

housing, bearing means in the latter, a pulley shaft insertible in said bearings, and a geared connection between the selected drive shaft and the pulley shaft.

2. In a drilling machine, the combination 70 with a housing having a drive shaft receiving portion and a front bearing portion, of a spindle movable in the latter, a series of different spindle driving shafts, bearings in the drive shaft receiving portion of the housing to receive any one of said shafts without change, a removable top part for the drive shaft receiving portion of the housing, bearings in the latter, a pulley shaft insertible 75 in said bearings, a gear on the pulley shaft, a gear on the selected drive shaft in mesh with the gear on the pulley shaft, and removable means applied to the ends of said shafts for holding them within the housing for a geared connection with each other.

3. In a drilling machine, the combination 80 with a housing having a drive shaft receiving portion and a front bearing portion, of a spindle movable in the latter, a series of different spindle-driving shafts, bearings 85 in the drive shaft receiving portion of the housing to receive any one of said shafts without change, a removable top part applied to the drive shaft receiving portion of the housing, bearings in the latter, a pulley shaft adapted to be slipped into said bearings, end plates adapted to be applied to the removable top part of the housing, a miter gear adapted to be applied to the pulley shaft and a miter gear adapted to be applied to the top part of the selected drive shaft for mesh with each other, a nut applied to the pulley shaft and nuts applied to the selected drive shaft to hold them in proper gear connection with each other within the 90 housing.

4. In a drilling machine, the combination 95 with a housing, of a spindle vertically mounted in the latter, a tubular drive shaft for said spindle also vertically mounted in the housing, and pump means operatively connected to said drive shaft at its lower end to force oil through it for discharge at its upper end.

5. In a drilling machine, the combination 100 with a housing, of a spindle vertically mounted in the latter, a tubular drive shaft also vertically mounted in said housing, a series of vertical intermediate shafts operatively connected between the spindle and the drive shaft, and a gear pump operatively connected to the lower end of the latter for forcing oil through it to be discharged at its upper end for descent around it and the intermediate shafts and spindle, for the 105 purpose specified.

6. In a drilling machine, the combination 110 with a housing, of a spindle vertically mounted in the latter, a horizontal pulley shaft in said housing, a miter gear on the 115

latter, a tubular drive shaft vertically mounted in said housing, a miter gear on the upper end of the drive shaft in mesh with the miter gear on the pulley shaft, a train of 5 gearing interposed between the drive shaft and spindle to rotate the latter, and gear pump means operatively connected to the lower end of the drive shaft for forcing oil through the latter to be discharged from 10 its upper end upon its miter gear, by which it is thrown upon it, the train of gearing and the spindle, for descent around them.

7. In a drilling machine, the combination with a housing having an opening in its 15 lower end, of a tubular drive shaft vertically mounted in said housing over said opening, a nut screwed into said opening below said shaft and containing two gear receiving cavities in its bottom portion, a pair of oil pump 20 gears in mesh with each other in said cavities, a bottom plate secured to said nut below the gears, one of said gears having

an upwardly projecting tubular shaft portion for connection to said drive shaft, said gear having a central hole which communicates with the hole in its tubular portion and through it with the hole in said drive shaft, the housing being constructed to act as an oil reservoir, said nut containing a hole leading from the latter to the gear cavities, the 25 bottom plate containing a pump discharge hole, and a hole directly under the gear which is turned by the drive shaft, said holes not extending all the way through the bottom plate and being connected by 30 a lateral hole in the latter, and a plug in the outer end of said lateral hole, whereby oil is adapted to be forced through said holes by the gears when rotated by the drive shaft, into and through the latter for 35 discharge from its upper end.

In testimony whereof I have hereunto set my hand this 30th day of July, 1923.

FRANK W. DINE.

173

Certificate of Correction.

It is hereby certified that in Letters Patent No. 1,570,050, granted January 19, 1926, upon the application of Frank W. Dine, of Minster, Ohio, for an improvement in "Drilling Machines," errors appear requiring correction as follows: In the drawings, Sheet 2, containing Figures 2 and 3, should appear as attached herewith instead of as shown in the drawings; Sheet 4, containing Figure 8, should appear as attached herewith as part of the Letters Patent; in the heading of the drawings, line 3, for "3 sheets" read 4 sheets; page 1 of the printed specification, line 54, after the word "latter" and before the period insert a comma and the words *and Figure 8 is a view on the line 8—8 of Figure 2*; page 4, after line 41 add the following as claim 8:

3. In a drilling machine, a series of interchangeable driving shafts, a support provided with bearings for said driving shafts, a movable spindle, bearings therefor in said support, said spindle being operable by said drive shafts, anyone of the drive shafts being insertable in the bearings without change, a part of said support being removable for the reception of said drive shafts, bearing means in said removable part, a pulley shaft insertable in and readily removable from said bearings, and gearing between the pulley shafts and the drive shafts;
and that the said Letters Patent should be read with these corrections therein that the same may conform to the record of the case in the Patent Office.

Signed and sealed this 25th day of May, A. D. 1926.
